UNITED STATES PATENT OFFICE.

FRANK C. WHITE, OF MERIDEN, CONNECTICUT, ASSIGNOR TO THE WILCOX & WHITE COMPANY, OF MERIDEN, CONNECTICUT, A CORPORATION OF CONNECTICUT.

AUTOPNEUMATIC MUSIC-PLAYING INSTRUMENT.

No. 852,813.

Specification of Letters Patent.

Patented May 7, 1907.

Application filed April 23, 1906. Serial No. 313,127.

To all whom it may concern:

Be it known that I, FRANK C. WHITE, a citizen of the United States, residing at Meriden, county of New Haven, Connecticut, have invented certain new and useful Improvements in Autopneumatic Music-Playing Instruments, of which the following is a full, clear, and exact description.

My invention relates to improvements in automatic piano players or pneumatic music playing instruments.

This invention relates mainly to an improvement in that mechanism made the subject matter of my former application, Serial No. 503,748, filed March 14th, 1906.

My object is to provide an improved tension regulating appliance which will automatically control the low tension in the wind-chest and hold the same substantially uniform irrespective of the tension in the bellows or exhaust chamber, the apparatus being also so constructed that whenever desired and for whatever purpose desired, the tension in the wind-chest may be instantly changed from high to low, and vice versa.

Figure 1 is a vertical section of certain parts of a pneumatic piano or music playing instrument of well known construction, but fitted with my new improvement. Fig. 2 is a section on the plane of the line X—X in Fig. 1, the upper part of the wind-chest being broken away, and the parts being shown in position to regulate and control the low tension in the wind-chest. Fig. 3 is a similar sectional view of the same parts, the latter being in a position for high tension in the wind-chest. Fig. 4 is a sectional view corresponding to Fig. 3, but showing a modification, the parts being in position for regulating the low tension. Fig. 5 is a similar view of the parts shown in Fig. 4, said parts being in position for high tension.

It will be unnecessary for me to describe in detail the various parts of the action mechanism, since my invention is not dependent thereon. I will, however, refer briefly to such parts in order that the importance of my invention may be fully comprehended.

1 is a key, which, when depressed, sounds a note.

2 is the lever or key-striking finger. This lever or key-striking finger is actuated through suitable connecting devices by a

power pneumatic 3. The operation of this power pneumatic is controllable by valve 4. 55 The moment of operation of the valve 4 is determined by valve 5, and the moment of operation of valve 5 is determined by a perforation in note sheet 21, which traverses a tracker 22. When a proper perforation registers with the duct leading to the pneumatic for valve 5, the action responds and a note is sounded.

6 represents a part of the space within the wind-chest.

7 is an exhaust chamber. This exhaust chamber is in communication with the wind-chest.

Air being drawn from the wind-chest takes the following course: It enters the space 8 in the upper part of a pipe or trunk 9. It then passes through the port 10 into the bellows 11. From the bellows 11 it passes through a port 12 and into the lower part 13 of pipe 9. From thence it goes directly into the exhaust chamber 7. 14 is a fixed partition in the pipe or trunk 9. 15-15^a are two sections of a valve, the function of which is to control and determine the freedom of passage of air from the wind-chest to the exhaust chamber. In 7c the preferred form, this valve is located within the bellows 11 and controls the size of the port 12. 16 is a connection between the section 15 of the valve and the back of the bellows 11. 17 is a small power pneumatic, the 85 moment of operation of which is controllable by the perforated note sheet. When a suitable perforation in the note sheet comes over the proper opening in the tracker, air is admitted through the duct 19 to suitable valve mechanism, which, when operated, will cause the bellows 17 to act in a direction to move and open the section 15^a of the valve, thus permitting the air to flow more freely through the port 12. In the preferred form, 18 is a 90 tappet rod connecting the movable back of bellows 17 with the section 15^a of the valve. 19 is a spring normally causing said section 15^a to stand closed or in the position indicated in Fig. 2. 20 is a spring which normally tends to open or distend the bellows 11. When the bellows 11 is opened to its greatest extent, the section 15 of the valve is opened to its greatest extent. As soon, however, as air is exhausted at 7, it would 100 tend to draw air through the bellows 11 from

95 105

the wind-chest 6. As this tension increases within the exhaust chamber, the tendency will be to cause the bellows 11 to collapse. This will move the valve section 15 so as to 5 restrict the freedom of passage of air through the port 12. The degree to which this bellows 11 collapses is determined by the degree of tension within the exhaust chamber 7. The degree to which the bellows 11 is collapsed 10 determines the position of the section 15 of the valve, and hence this determines the degree of exhaustion in the wind-chest 6 and maintains the same substantially uniform. As a result it follows that the power pneumatics 3 will operate with uniform force.

It is sometimes desirable to change quickly from the normal low tension to high tension in the wind-chest 6. Whenever that change is desired, the pneumatic 17 is operated, 20 opening the section 15^a of the valve and giving the utmost freedom of communication between the wind-chest 6 and the exhaust chamber 7; hence, at that moment the tension in the former will jump up to substantially that of the latter. The moment it is desired to reduce the tension again, the pneumatic 17 ceases to operate, the valve section 15^a closes, and the tension in the wind-chest 6 drops back again, and is, as before mentioned, held at a uniform point by the regulator section 15.

Hereafter I will refer to the section 15 as the tension governing section, and to the section 15^a as the high tension section, of the 35 valve. As shown in Fig. 2, the parts are in position to maintain and control the low tension in the wind-chest 6. In Fig. 3, the same parts are shown in a position to permit high tension in the wind-chest 6.

40 In Figs. 4 and 5, I have shown a modification in which the sections of the tension regulating valve are hinged in the middle, rather than at one end, as shown in Figs. 2 and 3. Otherwise the construction is identical with 45 that shown in Figs. 2 and 3. In this construction 15^b represents the tension governing section of the valve, and 15^c is the high tension section of the valve; otherwise similar reference numerals apply to the corresponding parts shown in Figs. 2 and 3. In 50 the modification shown in Fig. 4, it will be

observed that movement of the high tension section 15^c will not involve any movement of the tension governing section 15^b, and less work is therefore required of the power pneumatic 17. In this construction, the tension governing section 15^b is always in a position to govern.

From the foregoing it will be seen that air exhausted from the wind-chest always flows 60 through a single course or passage, and its course is always through the bellows 11, whether for high or low tension. By this arrangement I have found the action to be very sensitive and quickly responsive. Furthermore, it results in great compactness, since it entirely does away with the necessity of any auxiliary or independent passage or wind-way, such as employed prior to my inventions.

70 What I claim is:

1. In an auto-pneumatic musical instrument, or the like, a wind-chest, an exhaust chamber, a single passage affording communication between said exhaust chamber and said wind-chest, a bellows, the course of said passage extending through said bellows, a valve in said passage, said valve comprising two sections, one a tension governing section, the other a high tension section, the position of the tension governing section being controlled by said bellows, and automatically operated means for controlling the high tension section of said valve.

80 2. In an auto-pneumatic musical instrument, or the like, a wind-chest, an exhaust chamber, a single passage affording communication between said exhaust chamber and said wind-chest, a bellows, the course of said passage extending through said bellows, a valve in said passage, said valve comprising two sections, one a tension governing section, the other a high tension section, the position of the tension governing section being controlled by said bellows, and a power pneumatic for controlling said high tension section, said power pneumatic being controlled 85 from the tracker.

90 FRANK C. WHITE.
